UNITED STATES PATENT OFFICE.

JOHN F. STANDISH, OF WINTHROP, MASSACHUSETTS, ASSIGNOR TO UNITED SHOE MACHINERY CORPORATION, OF PATERSON, NEW JERSEY, A CORPORATION OF NEW JERSEY.

WAX POT.

Application filed April 22, 1921. Serial No. 463,503.

To all whom it may concern:

Be it known that I, JOHN F. STANDISH, a citizen of the United States, residing at Winthrop, in the county of Suffolk and State of Massachusetts, have invented certain Improvements in Wax Pots, of which the following description, in connection with the accompanying drawings, is a specification, like reference characters on the drawings indicating like parts in the several figures.

This invention relates to waxing and polishing and is herein shown as embodied in a machine for burnishing the heels of boots and shoes.

In machines of this character, employing a wax receptacle from which wax is transferred to a burnishing tool, it is customary for the operator to place pieces of wax in solid form in a heated receptacle. It is a difficult matter to estimate the amount of liquid wax which these pieces of solid wax will produce and, as the latter liquefy, the wax is apt to flow over the sides of the reservoir and down, over the frame or on to the floor. Again, the application of the heat has not been effected with sufficient economy. Usually the heating device is applied near the center of the reservoir which results in maintaining all the wax in substantially the same condition of fluidity. Furthermore, when the wax has solidified over night and it is desired to start the machine in the morning, the heated receptacle first causes the outside of the wax to melt. Then the wax feeder or transerrer is likely to lift or turn the whole chunk of solid wax which may shatter and be scattered about the floor. The necessity for melting a large amount of wax also causes delay in starting the machine.

It is an object of my invention to produce a device of this character which will obviate the above mentioned and other deficiencies. In accordance with one feature, the wax pot is divided into a comparatively small compartment under which the heat is concentrated and a connected and larger supply compartment extending further from the source of heat. Thus a small supply of thoroughly melted wax is always available and it is unnecessary to heat it all to the melting point. The dividing wall prevents any considerable body of congealed wax

from being disturbed when the wax feeder is started and, to make it possible to begin the burnishing sooner when the wax is congealed, I preferably provide the wax feeding wheel with a preheating device which melts the wax immediately around the wheel to allow its prompt rotation. In the illustrative construction, the wax pot is provided near the liquid wax compartment with an overflow pipe which limits the depth of wax around the wheel to prevent splashing and conducts any surplus wax into a drip pan to save it.

These and other features and advantages of the invention are fully set forth in the following description considered in connection with a preferred illustrative construction in which,—

Fig. 1 is a rear elevation, partly in section;

Fig. 2 a top plan view, partly in section;

Fig. 3 a right-hand end elevation;

Fig. 4 a rear view of the wax pot with a gas heating appliance;

Fig. 5 a section on the line 5—5 of Fig. 4.

In the illustrative construction, the wax supplying and feeding instrumentalities are mounted below and to the rear of the rotary burnishing tool. To a stationary hollow shaft 2 are fixed a flanged bushing 4 and a collar 8 between which is mounted for angular adjustment a sleeve 10 formed as a part of the arm 12 which supports the wax feeding mechanism. To turn the sleeve angularly to adjust the wax feeding mechanism with reference to the burnishing tool, the sleeve 10 is provided with an integral lug 14 against which engages a hand-screw 16 threaded through a lug 6 on the bushing 4. On the end of the supporting arm 12 is a wax pot 20 mounted adjacent to the burnishing iron 22 which may be formed in sections carried by springs 24 fixed to the drive shaft 26.

To prevent the scattering of solid wax when the machine is first started and to reduce the amount of heat which is required to keep a sufficient quantity of liquid wax available, the wax pot 20 is divided into connected compartments. As shown, there is a comparatively large compartment 28 for cold wax, and a smaller compartment or well 34 for liquid wax, these being separated by a partition 30 having an aperture at 32

to allow the passage of wax. In the well 34 is mounted a wax feeding wheel 36 which conveys the liquid wax to the burnishing tool. This wheel is mounted to rotate in a bracket 38 extending from the arm 12 and is driven by a shaft 40. To avoid the necessity for heating a large quantity of cold wax and to enable the machine to be started sooner when the wax is congealed, the wheel 36 is provided with an auxiliary heating means or preheater. As shown, a gas burner 42 is supported in a lug extending from the bracket 38 and is arranged to direct the heat against the face of the wheel.

15 To prevent an excessive supply of solid wax melting and overflowing the sides of the wax pot and to limit the amount the wheel 36 projects into the liquid wax, there is provided a pipe 44 formed as a portion 20 of the partition 30 and terminating below the level of the rim of the wax pot to limit the depth of the liquid wax. The pipe extends down through the bottom of the wax pot over a drip pan 46 which collects the 25 surplus wax. Also formed as a portion of the partition is an auxiliary wax pot 48 for another kind of wax, such as the black wax used more especially for filling the cracks or checks in pieced heels. To concentrate the heat on a small portion of the wax to keep it liquid and to cause the rest to melt gradually, the wax pot is enlarged 30 at 50 and bored to receive an electric heating unit 52 mounted directly under the liquid well 34. The heat is conveyed from the bottom of the wax pot directly to the liquid in the well and through the liquid to the wax feeding wheel 36. The heating unit is connected by leading-in-wires 54 and 35 a coupling 56 to wires extending through the hollow shaft 2. When an electric heating means is not available, the wax pot may be heated by means of gas. As shown in Figs. 4 and 5, the enlargement 50 is provided with an opening 60 having diverging sides into which projects a device heating by combustion such as a gas burner 62 mounted in an extension 64 of the bracket 12. Since the heating unit is removed when 40 a gaseous burner is used, the bore through the enlargement 50 serves as a flue for the burning gas which divides and spreads in opposite directions from the opening 60.

45 Although the invention has been set forth in connection with a particular apparatus, it should be understood that the invention is not limited in the scope of its application to the particular apparatus shown and described.

50 Having thus described my invention,

what I claim and desire to secure by Letters Patent of the United States is:

1. In a burnishing machine having a rotary burnishing tool, a wax pot comprising a supply compartment for solid wax and a communicating well for liquid wax, a disc-shaped feed wheel mounted in said well, means for rotating the feed wheel to apply liquid wax to the tool, means for heating the wax pot to convey heat to the wax and to the wheel, means for applying a flame to the rotatable wheel at a point thereon which is above the waxpot and away from the tool to preheat the wheel, and means constructed and arranged to limit the depth of liquid in the wax pot and conserve the excess supply of wax. 75

2. A machine of the class described, having in combination, a burnishing tool, a wax pot, a wax feeding wheel mounted in the wax pot, means for rotating the wheel, means for heating the wax pot to convey heat to the wax and to the wheel, and auxiliary heating means arranged to direct a flame toward a constantly exposed part of the feeding wheel to allow its free rotation when the bulk of the wax in the wax pot is congealed. 85

3. A machine of the class described, having in combination, a burnishing tool, a wax pot, a wax feeding member movably mounted in the wax pot to supply wax to the burnishing tool, and means for supplying heat directly to the wax feeding member at a point above the wax to melt the wax immediately surrounding the movable feeding member quickly to loosen it from the congealed wax. 95

4. A machine of the class described, having in combination, a burnishing tool, a main wax pot having a transverse apertured partition, means for heating the wax pot to liquefy the wax, an auxiliary wax pot forming a portion of said partition, and an overflow pipe also forming a portion of said partition and terminating below the rim of the main wax pot to limit the depth of liquid wax. 105

5. In a machine of the class described, a wax pot having an opening constructed and arranged to receive an electric heating device or to act as a flue and a second opening arranged to receive a device heating by combustion and joined to an intermediate portion of the first named opening to allow 110 the flame to spread. 115

In testimony whereof I have signed my name to this specification.

JOHN F. STANDISH.
